STUFFING WITHIN BALL

William D. Young, Greenville, S. C.

Application May 1, 1945, Serial No. 591,380

7 Claims. (Cl. 226—19)

1

This invention relates to a machine for stuffing containers with fibrous, resilient, or waste material or any other suitable material, to be hereinafter referred to as stuffing material, to form toys such as play balls, soft balls, animal figures and the like. These containers are usually made of fabric, leather and the like and are usually made from sewing a plurality of pieces together, leaving a small opening through which the material is forced to stuff the container with stuffing material such as wool waste, cotton waste, vegetable fibers, small pieces of rubber and the like, any and all of such material being hereinafter referred to as stuffing material.

It is the object of this invention to provide a machine having a nozzle with screw means for feeding stuffing material such as wool waste, cotton waste, vegetable fibers, small pieces of rubber and the like into the container or shell until the stuffing material has reached a pre-determined density at which time the mold holding the ball or other object being stuffed automatically opens and the machine automatically stops.

It is another object of this invention to provide a machine for stuffing play balls, toys and the like comprising a hopper into which stuffing material is adapted to be placed together with screw means for feeding the stuffing material into a converging cone, said cone having a nozzle with the screw member extending therewith and a flexible shell for a ball, toy figure and the like, is adapted to be placed over the nozzle and the waste material is fed therewith and a separable mold encases the ball being stuffed and the stuffing material is stuffed into the ball until it is stuffed to a pre-determined density at which time the mold automatically opens and the machine automatically stops and the ball or other toy figure is removed from the mold ready to be finished by sewing up the small opening left in the shell being stuffed and through which the stuffing operation has been effected.

It is another object of this invention to provide a machine for stuffing objects such as flexible shells for play balls, soft balls, toy figures and the like, said objects being composed of a flexible shell such as artificial leather, leather, fabric, and the like, which is usually sewed together from a plurality of pieces, leaving a small opening through which the ball is adapted to be filled with stuffing material such as vegetable fibrous material, waste wool, waste cotton, granulated rubber and the like. The machine em-

2

bodies a nozzle with screw means for feeding the stuffing material from a suitable hopper into the nozzle and the small opening left in the shell is inserted over this nozzle and the shell is surrounded by a suitable spring pressed mold, with suitable detents for holding the mold in closed position to hold the shell while it is stuffed to the desired shape, and when the shell has been stuffed with the stuffing material until a pre-determined amount of stuffing material has been stuffed into the ball, then the molds separate due to the increased pressure of the material being stuffed into the shell and the molds open and the machine automatically stops so that the finished stuffed article can be removed from the molds.

Some of the objects of the invention having been stated, other objects will appear as the description proceeds when taken in connection with the accompanying drawings in which:

Figure 1 is a front elevation of the machine;

Figure 2 is an end elevation looking from the lefthand side of Figure 1;

Figure 3 is a vertical sectional view taken substantially along the lines of 3—3 in Figure 2;

Figure 4 is an end elevation looking at the left-hand end of the machine in Figure 1;

Figure 5 is a top-plan view of the machine;

Figure 6 is an enlarged, detailed view of the lower central portion of Figure 5;

Figure 7 is a reverse or bottom-plan view of the structure shown in Figure 6;

Figure 8 is an enlarged detailed view of the upper right hand portion of Figure 2 but showing the mechanism on a larger scale;

Figure 9 is a horizontal sectional view taken substantially along the line 9—9 of Figure 8;

Figure 10 is an isometric view of the base portion of the mold which fits around the nozzle;

Figure 11 is a longitudinal sectional view taken through the mold and the nozzle and converging cone and screw for forcing the material into the bag within the mold;

Figure 12 is an enlarged detailed elevation of the upper right hand portion of Figure 8;

Figure 13 is an end elevation looking at the left hand portion of Figure 12 and from substantially along the line 13—13 in Figure 12;

Figure 14 is an elevation showing the shafting section of the cam means shown in Figure 12, with a portion broken away;

Figure 15 is a longitudinal sectional view taken through the converging cone member and the nozzle associated therewith and showing the

conical, rotary stuffing member associated therewith;

Figure 16 is an isometric view showing that portion of the mold disposed next to the machine and showing the hand of an operator holding an empty ball covering over the nozzle during the preliminary stages of the stuffing the ball covering full of waste material;

Figure 17 is an isometric view of the figure after it has been stuffed by this machine and removed therefrom and before the opening through which it was stuffed has been closed by a sewing operation;

Figure 18 is a longitudinal vertical sectional view taken through the clutch, and associated parts.

Referring more specifically to the drawings, the numerals 10 and 11 indicate the front posts of the machine, 12 and 13 indicate the rear posts. The rear posts are joined together by upper and lower horizontal struts 15 and 16 and the front posts are joined together by a board-like member 18 towards the top thereof. Strut 16 has an uprising board 20 resting thereon which serves as the rear end of the hopper. The sides of the hopper are indicated at 21 and 22. The front leg 10 and rear leg 12 are joined together by a horizontal strut 23 and the front leg 11 and rear leg 13 are joined together by a horizontal strut 24. The hopper has a sloping bottom 27 which slopes forwardly and joins to a small horizontal portion 28 which forms the bottom of the hopper into which the stuffing material such as waste wool, waste cotton, vegetable fibers, granulated rubber or any other suitable fibrous material in bulk may be placed.

A suitable electric motor 30 is mounted on the floor 31 and this has a V-pulley 32 thereon which has a V-belt 33 mounted thereon which in turn is mounted on a V-pulley 34, mounted on a shaft 35 which is rotatably mounted in bearings 36 and 37. These bearings 36 and 37 are mounted on cross members 38 and 39 supported by members 23 and 24. Shaft 35 has on the other end thereof a V-pulley 40 on which is mounted a V-belt 41, which in turn is mounted on a V-pulley 42 which is fixedly mounted on a main shaft 45, that is rotatably mounted in bearings 46 and 47. Bearing 46 is mounted on the horizontal bottom member 28, and bearing 47 is secured to the lower edge of strut 16. The main shaft 45 on the exterior of the machine has fixed thereon a V-pulley 50 which has a V-belt 51 thereon which is also mounted on a very much larger V-pulley 52 fixedly secured on a stirrer shaft 53, which stirrer shaft is mounted at one end in a bearing 54 mounted on top of board 29 and the other end is rotatably mounted in a portion of board 18. Stirrer shaft 53 has a conically shaped stirrer member 55 which has a plurality of prongs 56 thereon for stirring the stuffing material in the hopper to cause it to feed into the cone stuffing apparatus which will be presently described.

The main shaft 45 has slidably mounted thereon a collar 60 which fits against a clutch member 61, this member 61 having a keyway 62 thereon into which a key 63, mounted in shaft 45, slidably fits and loosely mounted on shaft 45 is the other half 65 of the clutch member which is secured on shaft 45. A collar 66 is fixedly secured on shaft 45 to withstand the pressure when clutch member 61 is moved against clutch member 65.

The adjoining surfaces of clutch members 61 and 65 are faced with suitable friction materials 68 and 69. Surrounding the member 60 and

pivotedly secured thereto as at 72 is a member 73 which is pivoted at its upper end as at 74 to a strut 75 which is fixed at its other end to the rear wall member 20. This member 73 projects downwardly and loosely passes between a pair of extended pins 77 and 78 which pins are fixedly mounted in a sliding bar 80 which is slidably mounted in guide members 81 and 82 which are secured on downwardly depending angle members 83 and 84.

A strengthening member 85 is also secured to the angle bars 83 and 84. The lower end of member 73 is pivotally connected as at 87 to a clutch rod 88 which is also slidably mounted in a bearing 89 secured to the lower edge of board 18. The clutch rod projects forwardly and has a pair of collars 91 and 92 adjustably secured thereon.

Mounted on angle member 93 is a pulley 94 over which a cable 95 passes, the upper end of this cable being secured as at 96 to sliding bar 80. Sliding bar 80 is normally pulled toward the front of the machine by means of a tension spring 97. The cable 95 passes downwardly and has its lower end secured to a treadle member 100 as at 101, the treadle member 100 being pivotally connected as at 102 to a block 103 which is secured to the floor 31. The angle bar 84 is secured by means of suitable bolts 105 to a cross bar 106 extending transversely of the frame work of the machine. Other transverse bars 107 and 108 are secured transversely of the machine to support the bottom member 28.

The front board member 18 has secured across the top portion thereof a sheet metal member 109 to increase the height of the front end of the hopper. Pivotally secured at its lower end to an angle bracket 110 is a bar 111. This bar has welded thereto a reenforcing bar 112. The collars 91 and 92 are disposed on the outer edges of these bars 111 and 112. Bar 111 projects upwardly and has fixedly secured on the upper end thereof a forked fitting 114 which has pivotally secured thereto as at 115 a bell crank dog 113 having a portion 116 on its longer end 118 and having a cam projection 117 on its shorter leg 119, the operation of which will be presently described.

Fixedly secured to the front wall 18 is a pair of angle bars 121 and 122. Rotatably secured between the outer ends of angle bars 121 and 122 is a shaft 123 which has secured thereon a cam member 124. A lever 125 is also fixedly secured on shaft 123 so that cam member 124 and lever 125 move together at all times. This cam member 124 has a notch 126 providing a tongue 127 which is engaged by the tongue 116 on the end 118 of bell crank lever 113. Cam member 124 has a projection 128 provided with a set screw 129 which is adapted to engage the sloping surface 130 of the longer arm 118 of bell crank 113 when a pre-determined amount of pressure has been built up within the shell during a stuffing operation.

The bell crank 113 is biased to engage tongue 127 by means of a tension spring 132 secured at one end thereto and having its other end secured to bracket 114. The lever 125 has secured thereto one end of a tension spring 135 whose other end is secured to a spring perch 136 whose other end is secured to angle bar 120. Secured to front wall 18 is a leaf spring member 137 whose upper end is adapted to engage a notch 138 in the upper end of the lever 125 to hold it in set position as shown in Figure 8 until a pre-determined amount

of pressure causes the release of tongue 116 from tongue 127.

The bars 121 and 122 are reenforced by means of a pair of bars 140 and 141 having their lower ends secured to vertical strap members 143 and 144 and the upper ends are secured to the horizontal bars 121 and 122. Shaft 45 has a coupling 150 on the end thereof to which is coupled shaft 151 of a conically shaped screw conveyor 152 which has a spiral vane 153 thereon terminating in a cylindrical or auger portion 154. This conical screw conveyor is surrounded by a conical housing 156 also having a spiral rib 157 on its interior surface cooperating with the spiral rib on vane 153 on the conical screw conveyor 152. The augerlike portion 154 is surrounded by a cylindrical nozzle member 158 which is secured by means of screws 159 to the restricted open end of the conical housing 156. It is over this cylindrical portion 158 that an opening 145 in a shell 146, to be stuffed is adapted to be fitted so as to convey the stuffing material into the interior of the ball, toy, or other flexible container which is to be stuffed by the machine.

The ball shell 146 is composed of a plurality of segments 147 sewed together. The proximate edges of two adjacent segments have each a row of stitches 148 formed therein before or after the segments are stitched together at their end portions. This leaves the opening 145 through which the waste fibers 149 are stuffed. When the shell is stuffed it is taken from the molds and appears as shown in Figure 17. Then a needle and thread can be passed through the stitches 148 to close the opening 145.

The conical housing 156 is secured at its larger open end to the front wall 18 by means of a plurality of straps 161 which have one end secured to the housing 156 by means of rivets or bolts 162 and bolts 163 at the other ends are embedded in the front wall 18 to hold the conical housing 156 in position over a circular opening 165 in front wall 18 and through which the stuffing material is fed from the hopper and by the screw conveyor into the article being stuffed.

One half of a mold member 171 has secured to opposed sides thereof rectangular members 173 and 174 which have suitable holes therein which are penetrated by the rods 169 and 170. A pair of rods 169 and 170 have one of their ends secured to bars 166 and 167. The rods 169 and 170 have collars 175 and 176 adjustably secured thereon for limiting the movement of the mold portion 171 toward the wall 18 under the influence of tension springs 178 and 179 which are secured at one end to pins 180 and 181 on members 173 and 174 and the other ends are secured to spring perches 182 and 183 secured to the front wall 18 of the machine. The outer ends of rods 169 and 170 are supported by a bar 168, which is supported by bars 172 and 164.

The mold portion 171 of the mold has a concave portion 185 which has an opening in its central portion which is adapted to slidably fit over the cylindrical portion 158 secured to the discharge end of the conical housing 156.

Pivotedly secured as at 190 and 191 on the members 173 and 174 are bell crank dogs 192 and 193. The horizontal portion of these dogs has a notch 184 for engaging a pin to be presently described. The uprising legs of the dogs 192 and 193 have fixedly secured thereto the two legs of an inverted U-shaped member 194.

Secured to the central upper surface of U-shaped member 194 is an angle bracket 195 which

slidably receives a shaft 196 which has its other end fixedly secured to the front wall 18 of the machine. This shaft 196 has a collar 197 fixedly secured thereon to limit outward movement of angle bracket 195 and U-shaped member 194. There is another collar 198 fixedly secured on shaft 196 and between collar 198 and angle bracket 195 is a compression spring 199 surrounding the shaft 196 and normally urging the U-shaped member and its associated dogs in a clockwise direction in Figure 8.

A second portion of the mold 200 has a semi-circular concavity 201 in the surface thereof which is proximate to the concave portion 185, the two concave portions 185 and 201 being complementary to form a cavity of the dimension desired for accommodating the article to be stuffed. This portion 200 of the mold has a U-shaped bracket 203 secured to its outer surface which surrounds the two bars 111 and 112.

On each side of the mold portion 200 is mounted rectangular members 205 and 206 which have suitable coinciding holes in their end portions which are slidably penetrated by the rods 169 and 170. These members 205 and 206 have outwardly projecting pins 207 and 208 which are adapted to fit into the notches 184 on the horizontal leg portions of dogs 192 and 193.

It will be observed that the notches 184 in the dog members 192 and 193 slope downwardly and outwardly and this angle of slope is made to correspond with the strength of compression spring 199 so that when the proper pressure has been built up in the article being stuffed in the mold, the outer portion 200 of the mold 200 will be moved outwardly to cause the horizontal portion of dogs 192 and 193 to rise upwardly to allow the mold section 200 to move away from mold section 171, but before this happens it is evident that the pressure will have moved mold section 171 away from the conical housing 156 to a certain degree before they are automatically separated by the pins 207 and 208 sliding out of the notches 184 in the dogs 192 and 193, respectively.

Immediately after the dogs release the pins 207 and 208, respectively, the pressure built up within the mold causes the mold 200 to strike the bars 111 and 112. While the molds are being pushed away from the wall 18 of the machine during a stuffing operation, cam member 124 will be rotating to a slight degree also, so that immediately after the two molds completely separate the set screw 129 will have engaged the sloping surface 130 to release tongue 127. Immediately after this happens the outer mold 200 continues to move outwardly to strike bars 112 and 111 and will move the clutch rod 88 to stop the machine.

In the drawings and specification there has been set forth a preferred embodiment of the invention, and although specific terms are employed, they are used in a generic and descriptive sense only, and not for purposes of limitation, the scope of the invention being defined in the claims.

I claim:

1. In a machine for stuffing objects having a flexible covering provided with an opening, a hopper for holding stuffing material, an opening in one side of the hopper having a funnel shaped member covering the opening; the smaller end of the funnel shaped member having a nozzle, a screw member mounted in the funnel shaped member and projecting into the nozzle, a pair of separable molds, one of which having a hole therethrough, through which the nozzle projects, the opening in the covering being adapted to be

inserted over the nozzle, the molds being adapted to be moved to enclose the covering while the same is stuffed full of the stuffing material, means for latching the two molds together, predetermined pressure responsive means for releasing the latching means when a predetermined pressure is built up by stuffing the material into the cover, the predetermined pressure of the material forcing the molds to separate after release of the latching means, and means operable by the separation of the molds for automatically stopping the machine.

2. Apparatus for stuffing objects having a flexible covering, provided with an opening, such as play balls, toys and the like, comprising a hopper for holding stuffing material, said hopper having an opening therein, a tapering hollow member having a nozzle on its smaller end, and means for securing its larger end over said opening, a screw member mounted in the tapering member, means for rotating the screw member to force the stuffing material through the tapering hollow member, a pair of separable members, the proximate surfaces of said members each having a cavity therein which collectively conform to the shape of the object to be stuffed, one of said members having a hole extending from its cavity to its remote side and penetrated by said nozzle of the tapering hollow member, the covering of the object to be stuffed being adapted to have its opening inserted over the nozzle of the tapering hollow member, movable means for latching the separable members together to form the cavity for shaping the object to be stuffed, means responsive to a predetermined amount of pressure of material within the covering for unlatching the latching means to allow the members to move apart from each other, and means operable by movement of the separable members apart from each other for automatically stopping rotation of the screw member.

3. Apparatus for stuffing a suitable flexible covering having an opening therein to form an object such as a play ball, toy and the like, comprising a hopper having a hole therein for holding stuffing material, a funnel-shaped member having its larger end secured to the exterior of the hopper and covering said hole, a screw mounted in the hopper and extending into the funnel-shaped member, means for rotating the screw, a pair of separable retaining members each having a cavity in their proximate surfaces, one of which is provided with a bore for receiving the discharge end of the funnel-shaped member, the cavities and the retaining members when they are moved in face to face relation forming a closed cavity of the shape of the object to be stuffed, the opening in the covering being adapted to be inserted over the smaller end of the funnel-shaped member, movable means for latching the two separable members together, means responsive to a predetermined pressure in the material within the flexible covering for moving the latching means to unlatching position, and means engageable by one of the separable retaining members when it is moved to separated position relative to the other retaining member by the pressure of the material in the stuffed article for automatically stopping the means for rotating the screw.

4. Apparatus for stuffing a flexible covering having an opening therein with stuffing material comprising a pair of separable retaining members each having a cavity in their proximate surfaces to form a compartment for the cover-

ing being stuffed, one of the members having a hole therethrough, means projecting through said hole and through the opening in said covering for forcing stuffing material through said opening into the covering to fill the covering with stuffing material while disposed in the cavity formed by said retaining members, means for latching the two retaining members together, means responsive to a predetermined amount of pressure of the material within the covering for unlatching the latching means to allow the two retaining members to move apart from each other and means operable by the movement of the retaining members apart from each other for automatically stopping the means for forcing stuffing material into the covering.

5. Apparatus for forcing stuffing material into a suitable flexible container having an opening therein which comprises two juxtaposed separable retaining members having a cavity in at least one of their proximate surfaces to conform to the shape of the object being stuffed, one of the retaining members having a hole therethrough communicating with said cavity, means for latching the retaining members together, means for forcing stuffing material through the hole in one of the retaining members and through the opening in the container, means responsive to a predetermined pressure of the material within the flexible container for unlatching the latching means to allow the retaining members to move apart from each other, and means controlled by the movement of one of the retaining members when the retaining members are unlatched from each other for automatically stopping the means for forcing the stuffing material into the container.

6. Apparatus for forcing fibrous material into a flexible covering having an opening therein for forming an object such as a play ball, toy and the like, comprising a hopper for holding the fibrous material, a pair of separable retaining members having a cavity in the proximate surfaces of at least one of the retaining members of a shape conforming to the object being stuffed, one of the retaining members having a hole therethrough, a funnel-shaped member having its larger end secured to the exterior of the hopper and said hopper having an opening therein forming communication between the funnel-shaped member and the interior of the hopper, a screw member mounted in the funnel-shaped member for forcing fibrous material through the funnel-shaped member and through the hole in one of the retaining members and into the covering disposed in the cavity between the separable retaining members, means for rotating the screw member, means for latching the two retaining members together, control means for the screw driving means, means for latching the control means in a position to connect the screw to a suitable power driven means, resilient means holding the control means in latched position, means responsive to a predetermined pressure of the material within the flexible covering for unlatching the first latching means to allow the two retaining members to move apart from each other to exert pressure on the control means to move its latching means to unlatching position, and to move the control means to disconnect the screw means from its driving means.

7. Apparatus for stuffing a flexible covering for a play ball, toy and the like, said covering having an opening therein, means for forcing fibrous

material through the opening in the covering to stuff the same full of stuffing material, a pair of movably mounted retaining members recessed on their proximate sides to form a cavity when they are moved together for shaping the covering being stuffed full of material, means for latching the retaining members together during a stuffing operation, pressure responsive means for holding the latching means in latching position, the pressure responsive means being operable by a predetermined amount of pressure of the material within the covering to unlatch the latching means, and means operable by movement of the retaining members to separat-

ed position for stopping the means for forcing the fibrous material into the covering.
